UNITED STATES PATENT OFFICE.

HENRY K. MYERS, OF SWISSVALE, PENNSYLVANIA.

RAIL CROSS-TIE.

No. 858,528.

Specification of Letters Patent.

Patented July 2, 1907.

Application filed March 28, 1907. Serial No. 365,148.

To all whom it may concern:

Be it known that I, HENRY K. MYERS, a citizen of the United States, residing at Swissvale, in the county of Allegheny and State of Pennsylvania, have invented certain new and useful Improvements in Rail Cross-Ties; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention has for its objects the provision of a rail support which can be produced with a minimum amount of material, at a minimum cost, give a maximum support to the rails, distribute the train load evenly over the road-bed, be simple in construction, have maximum life, etc., which objects I attain in the construction and arrangements of parts as will be hereinafter fully described in detail, and later pointed out in the appended claims.

In the accompanying drawings, several views are shown; in which drawings,

Figure I, is a plan of a short section of track. Fig. II, is a longitudinal view of a portion of the same. Fig. III, is an end thereof. Fig. IV, is a perspective of one of the supporting members. Fig. V, is a perspective of a portion of one of the rail clamping members, and, Fig. VI, a plan of the blank for forming the supporting member.

Similar reference numerals designate like parts throughout the following description.

The structure shown, comprises a pair of parallel disposed members or ties 1, which in this instance are shown as formed of inverted "T" beams, selected as best adapted to carry out my invention. The ties are connected to one another by a pair of rail supporting members 2, the supporting portion proper extending along in a horizontal plane at an elevation above the ties, said members being pressed into form from a sheet metal blank, as shown at, Fig. VI, said form having end walls 3, with laterally disposed portions 3', inclined side walls 4, with a space 5 between the ends of the same and the end walls, to engage over the upturned web of the tie members, said sides terminating in the laterally disposed portions 6, the extremities 7 of which are bent upwardly and thence downwardly over the webs of the tie members and extensions 3' of the end walls, the structure being secured to the tie members by rivets 8 or other means. Each of these supporting members is provided at the top with openings 8, which extend longitudinally therethrough, into which openings are placed the rail clamping members 9, to engage the rails 10, said members each having an opening 11 formed through the downwardly extended flange por-

tion near each end thereof and registering with the aforesaid openings or spaces 5 of the supporting member, into which openings and spaces are driven split-keys 12, thus firmly securing the rails in position upon the supporting members. 60

The structure is admirably adapted to fulfil the objects set forth, being buried in the road-bed to a point approximately on a level with the base of the rails, presenting a neat appearance.

Having thus fully shown and described a practical 65 and operative means to carry out my invention, what I claim is—

1. The combination of a pair of cross-ties connected to one another by a pair of hollow rail supporting members extending to an elevation above the ties in parallel relation with the rails, and means to secure the rails thereto. 70

2. The combination of a pair of cross-ties connected to one another by a pair of hollow rail supporting members extending to and on a plane in parallel relation with the rails, and means to secure the rails thereto. 75

3. The combination of a pair of cross-ties connected to one another by a pair of hollow rail supporting members extending to an elevation above the ties and in parallel relation with the rails, a pair of rail engaging members carried by said supporting members, and means to secure 80 said rail members to said supporting members.

4. The combination of a pair of cross-ties connected to one another by a pair of hollow rail supporting members extending to and on a plane in parallel relation with the rails, rail engaging members carried by said supports, 85 and means to secure the rail members to the supporting members.

5. The combination of a pair of cross-ties connected to one another by a pair of rail supporting members extending to an elevation above the ties in parallel relation with 90 the rails, and means between the rails and supporting members to secure the rails thereto.

6. The combination of a pair of cross-ties connected to one another by a pair of rail supporting members extending to an elevation above the ties and in parallel relation with the rails, a pair of rail engaging members arranged 95 between the rails and supporting members, and means to secure the same thereto.

7. The combination of a pair of cross-ties connected to one another by a pair of rail supporting members extending to and on a plane in parallel relation with the rails, rail engaging members extending between the rails and supports, and means to secure the rail engaging members to the supporting members, said supporting members being of approximately arch-shape in cross-section. 100

8. The combination of a pair of cross-ties connected together by a pair of rail supporting members extending to an elevation above the ties in parallel relation with the rails, a pair of rail clamping members extending from between the supporting members and rails, each of which 110 is provided with a groove along its edge to engage the edges of the rail base, and means to secure the said clamping members to the supporting members.

9. The combination of a pair of cross-ties connected together by a pair of rail supporting members extending to an elevation above the ties in parallel relation with the rails, a pair of rail clamping members arranged between the supporting members and rails, each of which is provided with a groove along its edge to engage the edges of the rail base, and means to secure the clamping members 115 120

to the supporting members, said supporting members each constructed of a single piece of sheet metal and approximately of arch shape in cross-section.

10. The combination of a pair of cross-ties having an upwardly extended flange, of a pair of sheet metal rail supporting members of approximately arch shape in cross section and having transverse grooves at the ends to engage over the upturned flanges of the cross-ties, a pair of rail clamping members arranged between the supporting members and rails, each of which has a groove along its edge to engage the edge of the rail base, and means to secure said clamps to the supports.

11. The combination of a pair of cross-ties, and a pair of rail supporting members connected to and extending transversely of said ties, said supporting members being

each provided at the top with an opening extending longitudinally thereof.

12. The combination of a pair of cross-ties, and a pair of hollow rail supporting members connected to and extending transversely of said ties, each of said supporting members being of approximately arch-shape in cross-section and having an opening extending longitudinally in the top and partially down each end. 20

In testimony whereof I affix my signature, in presence of two witnesses.

HENRY K. MYERS.
